TWISTED STRANDS AND THE METHOD OF
PRODUCING SAME

Winfred M. Brooks, West Orange, N. J.

Application November 21, 1933, Serial No. 698,954

3 Claims. (Cl. 117—52)

This invention relates generally to strands of material, and has more particularly reference to a method of twisting a flat and one or more round wires together and to the product obtained thereby, its main object and feature being the production of a wire strand that has greater gripping power than those heretofore used in connection with seals made of compressible material such as lead.

10 In the accompanying drawings, the invention is disclosed in several concrete and preferred forms in which:

Fig. 1 is a view, partly in section and partly in elevation, of one form of wire twisting machine 15 that may be used in carrying out the process and producing the product;

Fig. 2 is view, partly in section and partly in elevation, of the device shown in Fig. 1 looking in the direction of arrow 2 in Fig. 1;

20 Fig. 3 is a detail sectional view of the upper part of the twisting frame and associated elements, looking at the parts in the same direction as in Fig. 1;

Fig. 4 is a detail sectional view of the lower part 25 of the twisting frame and associated elements, looking at the parts in the same direction as in Fig. 1;

Fig. 5 is a detail sectional view substantially on the plane of line 5—5 of Fig. 4;

30 Fig. 6 is a horizontal sectional detail view substantially on the plane of line 6—6 of Fig. 3;

Fig. 7 is a horizontal sectional detail view substantially on the plane of line 7—7 of Fig. 4;

Fig. 8 is more or less of a diagrammatic view 35 showing the beginning of the twisting action;

Fig. 9 is also a diagrammatic view showing the completion of the twisting action;

Fig. 10 is an enlarged fragmentary view of a 40 length of strand showing the wires when first twisted together;

Fig. 11 is a view similar to Fig. 10 but showing the wires when more fully twisted together;

Fig. 12 is a transverse sectional view substantially on the plane of line 12—12 of Fig. 11;

45 Fig. 13 is a sectional view substantially on the plane of line 13—13 of Fig. 11;

Fig. 14 is a view similar to Fig. 11 but showing a modified form of the invention in which a plurality of round wires are employed; and

50 Fig. 15 is a view in elevation of a seal made of compressible material in which the strand may be employed.

Referring first to Figs. 11, 12 and 13 it will be seen that 15 indicates a strand consisting of a flat wire 16 and a round wire 17 twisted together in

such way that the round wire is adjacent throughout to one and the same face 16a of the flat wire. Or, to put it differently, one face 16b of the flat wire is naked throughout and side edges 16c of the flat wire are exposed throughout; that is to say, the round wire does not at any time cross the side edges of the flat wire, but lies in one and the same helically extending trough of the flat wire throughout the strand. Turning now to Fig. 15, 5 18 indicates a body of compressible material, such as lead, in which one end 15a of the strand is embedded or molded in position. Said body is usually provided with two openings 18a and 18b through which the free end 15b of the strand is threaded, after which the body of lead is compressed in a manner well understood. It will now 10 be seen that, owing to the naked face of the flat wire and to its exposed side edges, the lead body will have a much firmer grip on the strand and it will be much more difficult than formerly to 15 dislodge it, and that this advantage is accomplished without materially increasing the diameter over that of a strand devoid of a flat wire but composed of two or more round wires twisted together. In Fig. 14 is shown a plurality of round 20 wires 17a and 17b lying in the trough formed by the same face of the flat wire. This is useful in 25 the same way as above described when employed in connection with a lead seal.

The particular means used to practice the 30 process and to produce the product may, of course, vary greatly, but by way of illustration the following device is disclosed:

19 is a stationary frame supporting various instrumentalities to be hereinafter described, the 35 chief one of which is a take-up reel 20. 21 indicates a twisting frame or head. 22 is a motor carried by a part of the framework and connected by means of coupling 23 to shaft 24 and mounted on the latter is the frame or head 21. 25 indicates an upper twisting roll and 26 a lower twisting roll. 27, 28 and 29 are guide rolls also carried by the twisting head. Mounted to rotate with the twister head is a gear 30 that meshes with pinion 31 on shaft 32, which latter is also carried by the 40 twister head. At the upper end of shaft 32 is a pinion 33 meshing with a stationary gear 33a carried by stationary frame 19. At the point where stationary pinion 33a is located, there is a lower bearing 34 for stationary frame 19, and the 45 purpose of shaft 32 and its gears is merely to provide a steady means for the parts. Shaft 24 carries at its upper end a pinion 35 that meshes with a pinion 36 on shaft 37 carried by stationary frame 19. Shaft 37 carries two worms 38 and 50 55

39 that mesh with worm gears 40 and 41 of feed as a unit, and a product substantially like that rollers 42 and 43 mounted on frame 19. Shaft 37 shown in Fig. 10 is obtained as the result of the carries a third worm 44 that meshes with worm action of roller 25. In the present instance it is gear 45 on shaft 46 also on frame 19, and this preferred to subject the strand to additional 5 shaft 46 is provided with a slip friction clutch twisting by means of roller 26 with the result that 47 that connects it with sprocket 48. Passing over a product substantially like that shown in Fig. 11 sprocket 48 is a sprocket chain 49 that drives is obtained. The finished product is then wound sprocket 50, of strand guide mechanism 51, and on the reel by the means previously described, and also drives sprocket 52 which carries a gear 53 10 that meshes with gear 54 of the take-up reel. It will be noted that the reel constitutes a pulling device that advances the two wires at equal speed. 10
15 that meshes with gear 54 of the take-up reel. It is unnecessary to describe the details of the strand guide mechanism, suffice it to say that it has a member that travels back and forth to lay the strand on the reel. At its upper end, frame 19 has a bearing 55 in the twisting frame 21.

Flat wire 16 and round wire 17 are led from suitable sources of supply (not shown) over guides 56 and 57 and through an aperture in bar 58, and thence down through opening 59 centrally of the twisting frame. The wires then pass over upper twisting roller 25, thence over guide rollers 27, 28 and 29, and then over lower twisting roller 26. From here the product passes through aperture 60 of shaft 24 and thence several times around feed rollers 42 and 43, and then 25 by way of strand guide mechanism 51 to the take-up reel. It will be noted from Fig. 8 that the twisting effect of twisting roller 25 is not merely to twist the flat and the round wires together, but 30 it also produces a preliminary twist of each wire 16 and 17 before they are brought together. The twist in the round wire is not visible, but in the flat wire it is. The result is that when the wires touch, the twisting action continues on the strand

5 as a unit, and a product substantially like that shown in Fig. 10 is obtained as the result of the action of roller 25. In the present instance it is preferred to subject the strand to additional twisting by means of roller 26 with the result that a product substantially like that shown in Fig. 11 is obtained. The finished product is then wound on the reel by the means previously described, and it will be noted that the reel constitutes a pulling device that advances the two wires at equal speed. 10

I claim:

1. As a new article of manufacture: a strand 15 consisting of a flat and one or more round wires twisted together, the round wire or wires lying throughout in one and the same helically extending trough formed by one face of the flat wire, the other face of the flat wire being naked throughout.

2. As a new article of manufacture: a strand 20 consisting of a flat and one or more round wires twisted together, the flat wire having its side edges exposed throughout, and the round wire or wires lying throughout in one and the same helically extending trough formed by one face of the flat wire. 25

3. The process of twisting a flat and one or 30 more round wires together which consists in: twisting said wires together and laying the round wire or wires, without crossing the side edges of the flat wire, in one and the same helically extending trough formed by one face of the flat wire.

WINFRED M. BROOKS.
